(57) **CLAIM**

The ornamental design for an industrial equipment with human machine interface assembly, as shown and described.

DESCRIPTION

FIG. 1 illustrates a front cross-sectional view showing our new design for an industrial equipment with human machine interface assembly.

FIG. 2 illustrates a front cross-sectional perspective view of the design for the industrial equipment with human machine interface assembly as shown in FIG. 1.

FIG. 3 illustrates a rear view of the design for the industrial equipment with human machine interface assembly as shown in FIG. 1.

FIG. 4 illustrates a right side view of the design for the industrial equipment with human machine interface assembly as shown in FIG. 1.

FIG. 5 illustrates a left side view of the design for the industrial equipment with human machine interface assembly as shown in FIG. 1.

FIG. 6 illustrates a bottom view of the design for the industrial equipment with human machine interface assembly as shown in FIG. 1; and,

FIG. 7 illustrates a top view of the design for the industrial equipment with human machine interface assembly as shown in FIG. 1.

The broken line showing of the industrial equipment with human machine interface assembly is for illustrative purposes of the environment only and forms no part of the claimed design.

1 Claim, 5 Drawing Sheets
